(57) **CLAIM**

The ornamental design for an electronic control device, as shown and described.

DESCRIPTION

FIG. 1 is a perspective view of an electronic control device showing my new design;

FIG. 2 is a right side elevational view of the electronic control device of FIG. 1;

FIG. 3 is a left side elevational view of the electronic control device of FIG. 1;

FIG. 4 is a front side elevational view of the electronic control device of FIG. 1;

FIG. 5 is a rear side elevational view of the electronic control device of FIG. 1;

FIG. 6 is a top side plan view of the electronic control device of FIG. 1; and,

FIG. 7 is a bottom side plan view of the electronic control device of FIG. 1.

The broken lines shown in the drawings illustrate portions of the electronic control device that form no part of the claimed design.
